JOHN G. BLESSING, OF CHICAGO, ILLINOIS, ASSIGNOR TO ALEXANDER E. KEITH, OF HINSDALE, ILLINOIS.

ELECTRIC CLOCK.

1,250,782.

Specification of Letters Patent.

Patented Dec. 18, 1917.

Application filed April 2, 1917. Serial No. 159,114.

To all whom it may concern:

Be it known that I, JOHN G. BLESSING, a citizen of the United States of America, and resident of Chicago, Cook county, Illinois, 5 have invented a certain new and useful Improvement in Electric Clocks, of which the following is a specification.

My invention relates to electric clocks or other instruments or devices in which the 10 clock-work or other mechanism is automatically re-wound or re-set to again tension the spring by which the clock or instrument is operated, the re-winding or re-setting being accomplished by an electro-magnet which is 15 intermittently or periodically energized, so that with a proper source of current the clock or other instrument or device will be operated by the spring or other means as long as there is a sufficient supply of current 20 to energize the magnet.

It will be seen that my invention is an improvement on the structure disclosed in Patent No. 1,217,557, granted February 27, 1917.

25 Generally stated, the object of my invention, as herein shown and described, is to provide an improved construction and arrangement whereby the ratchet-mechanism and electric switch are simplified, thereby to 30 reduce the cost of manufacture, and whereby the operation of these elements is rendered more certain and reliable.

It is also an object to provide certain details and features of construction and combinations tending to increase the general efficiency and reliability of a ratchet-mechanism and circuit-controlling switch of this 35 particular form and construction.

To these and other useful ends, my invention consists in matters hereinafter set forth and claimed.

In the accompanying drawings:—

Figure 1 is a rear elevation of a clock provided with a ratchet-mechanism and a 45 circuit-controlling switch embodying the principles of my invention, showing the rear portion of the casing removed to bring into view the different devices inclosed thereby.

Fig. 2 is a view looking in the direction of the arrows of line 2—2 in Fig. 1, showing only the back and sides of the casing in section.

Fig. 3 is an enlarged detail view of the ratchet-mechanism.

Fig. 4 is a view looking in the direction

of the arrows of line 4—4 in Fig. 1, only the sides and back of the casing being shown in section.

Fig. 5 is an enlarged detail perspective view showing the positions of the pawl and 60 detent of the ratchet when the circuit is opened.

Fig. 6 is a similar view showing the positions of said pawl and detent when the circuit is closed.

Fig. 7 is a diagram of the circuit by 65 which the magnet is energized.

As thus illustrated, my invention comprises a clock-casing A to the front wall of which the clock-work B, which may be of 70 any suitable character, is suitably secured. This clock-work preferably has a main gear-wheel b which rotates about the axis of the hands of the clock, and by which the train of gears is operated to actuate the escape- 75 ment C, which latter may also be of any suitable character.

The ratchet-mechanism and circuit-controlling switch for operating the clock, and for re-winding or re-setting the mechanism, 80 are constructed as follows: The bracket D is secured to the front wall of the clock and supports the electro-magnet d, which latter is of any suitable character. The armature E is disposed opposite the rear end of this 85 magnet, and is pivoted by a pin e upon the ears or lugs F mounted on said bracket. A spring f is wound on said pivot e and so arranged that it tends to move the armature away from the magnet. The spring arm G 90 is suitably connected with the armature, at its pivotal point, and is adapted at its other end to engage the ratchet-wheel g, which latter is mounted on a shaft H that extends at right angles to the axis of the armature, 95 but parallel with the axis of the gear-wheel b, being provided with a pinion h to engage said gear-wheel. Thus the ratchet is composed of the wheel g and the pawl or dog G, and hence the ratchet has a spring-pressed 100 pawl actuated by the spring f to drive the clock. When the magnet is energized, the end of the pawl G slides over the bevel of a ratchet-tooth and then drops into the next notch on the ratchet-wheel. A detent I is 105 suitably secured at i to the casing or housing of the clock, and has its free end portion adapted to bear against the end of the pawl G, when the armature is fully retracted (see Fig. 6), and to occupy another notch (see 110

Fig. 5) when the armature is fully attracted. With this arrangement, the end portion 1 of the pawl G and the end portion 2 of the detent I constitute the engaging elements of a switch for automatically opening and closing the circuit of said magnet. The spring *f* slowly retracts the armature E, causing the pawl G to slowly actuate the ratchet-wheel (because of the action of the escapement C), and as soon as the armature is fully retracted, so that the ratchet is fully actuated, the contact portion 2 of the detent drops into the same notch with the contact portion 1 of the pawl, thus automatically closing the circuit through the magnet. The energizing of the magnet, in this way, causes it to attract the armature E, thus forcing the pawl backward against the tension of the spring *f* and into another notch. While the contact portion 1 is moving between the ratchet-wheel and the portion 2, during the attraction of the armature E, a rubbing action takes place between these two portions 1 and 2, which insures clean contacts for the switch, thus insuring a closure of the circuit and the energizing of the magnet each time the two contacts come together. This sliding or rubbing action between the two contacts is terminated by the separation of the two contacts, as soon as the portion 1 rides over the point of the ratchet-tooth, so that the switch is opened by a direct separation of the two contacts in a direction substantially at right angles to the sliding movement of the one contact on the other. It will be understood, of course, that the ratchet-wheel *g* is made of insulating material, such as rubber vulcanite or red fiber, or any other suitable material, so that the ratchet-teeth are formed of non-conducting or insulating material, thereby preventing the electric current from passing through this ratchet-wheel, and whereby the magnet is not energized until the two metallic springs which form the pawl G and the detent I are brought together in one and the same notch of the ratchet-wheel.

The circuit connection can be of any suitable character, such for example as that shown in Fig. 7, the essential requirement, of course, being that the springs or switch-contacts G and I be connected in series in the circuit which includes the coil of the magnet, in a manner which will prevent short-circuiting and insure the desired results, and for this purpose may be of any suitable or desired character.

From the foregoing, therefore, it will be seen that the spring-pressed ratchet-pawl and one element of the electric switch are combined in a single flat spring G, which may be of spring brass, or other suitable material, and that the detent and other element of the switch are combined in a single flat spring I, which latter may also be of spring

brass or any other suitable material. Thus the mechanism is simplified, and in addition the manner in which the circuit is closed by the entering of the portion 2 into the same notch with the portion 1, so that the portion 2 is brought flatwise and crosswise onto the portion 1, insures greater certainty in the operation of the mechanism as a whole. With this construction and method of operation, less accuracy is required in the formation of the ratchet-teeth and other parts, and at the same time the circuit is not opened until after the rubbing or sliding action has taken place between the two contacts 1 and 2, and not until after the pawl is in position to enter the next notch. In other words, the construction prevents the opening of the circuit before the end of the pawl (which bears the switch contact portion 1) arrives in position to enter the next notch on said ratchet. In this way, there is no necessity of any movement of the armature toward the magnet after the circuit is opened, as the opening of the circuit is not dependent upon the momentum of the armature, and consequently the opening of the circuit is not liable to cause retraction of the armature before the pawl reaches the next notch. Thus the desired re-winding of the clock, so to speak, or the re-setting of the ratchet-mechanism, is insured each time the circuit is automatically closed.

From the foregoing it will be seen that the clock or other instrument has a ratchet for the operation thereof, a device to actuate said ratchet, which device, as shown and described, is the spring *f* which drives the train of gears in the clock; that said instrument also comprises an electro-magnet provided with an armature to re-set the ratchet after each operation thereof, and an electric circuit for said magnet, the ratchet device having a spring-pressed pawl G included in said circuit and connected with said magnet armature, and means co-operating therewith to control said circuit, which means include the switch contacts 1 and 2 arranged to prevent opening of said circuit before the pawl arrives in position to enter the next notch on said ratchet, whereby the pawl serves the double function of actuating the ratchet wheel and of conducting the current by which the magnet is energized. With this construction, the insulating material of which the ratchet wheel *g* is made serves to keep the circuit open during actuation of the ratchet by the spring *f*, for otherwise, and notwithstanding the air gap between the contacts 1 and 2 of the switch, the circuit would be closed between these contacts if said ratchet wheel were made of metal. It will be seen, therefore, that the invention serves to simplify the construction, as one strip of resilient metal serves not only as the pawl and the spring by which it is pressed

against the ratchet wheel, but also provides one of the contacts of the switch, so that the three things are embodied in one strip of sheet metal, thus obviating the necessity of using separate and distinct parts to perform these different functions.

I do not, of course, limit myself to the exact construction shown and described.

What I claim as my invention is:—

- 10 1. In an instrument of the class described, the combination of a ratchet for operating said instrument, a device (f) to actuate said ratchet, an electro-magnet (d) provided with an armature (E) to re-set said ratchet after each operation thereof, and a circuit for said magnet, said ratchet having a spring-pressed pawl G included in said circuit and connected with said armature and means coöperating therewith to control 20 said circuit, said means (1 and 2) including a switch arranged to prevent opening of said circuit before said pawl arrives in position to enter the next notch on said ratchet, one element (1) of said switch sliding on the other (2) during movement of the pawl by said magnet, said pawl by its spring-pressed action serving to open said switch after reaching the next notch, the one element being insulated from the other when the 30 switch is open, and said other element (2) of the switch being controlled by said ratchet to close the circuit after each actuation of the pawl by said device.
2. In an instrument of the class described, 35 the said combination and structure as set forth in claim 1, in which said pawl and one element are both formed by a single spring strip connected to said armature.
3. In an instrument of the class described, 40 the said combination and structure as set forth in claim 1, in which said switch is opened by movement of said one element in a direction approximately at right angles to said sliding motion.
- 45 4. In an instrument of the class described, the said combination and structure substantially as set forth in claim 1, in which said one element (1) is supported by and has all the movements of said pawl.
- 50 5. In an instrument of the class described, the said combination and structure (substantially as set forth in claim 1) in which said armature is mounted to swing about an axis disposed at right angles to the axis of said ratchet.
- 55 6. In an instrument of the class described, the said combination and structure as set forth in claim 1, in which said ratchet in- eludes a series of teeth forming said insulation, and in which said switch is formed by 60 two springs which engage said teeth, the two springs occupying adjacent notches when the circuit is opened, and said springs occupying the same notch when the circuit is closed. 65
7. In an instrument of the class described, the said combination and structure as set forth in claim 1, in which said other element is carried by a member which forms a detent (I) for said ratchet, and in which said pawl and detent occupy the same notch when the circuit is closed. 70
8. In an instrument of the class described, the said combination and structure as set forth in claim 1, in which the two elements 75 of the switch occupy adjacent notches when the circuit is opened, and occupy the same notch when the circuit is closed.
9. In an instrument of the class described, the said combination and structure as set 80 forth in claim 1, in which said ratchet has a detent (I) to prevent backward operation thereof, said pawl and detent occupying adjacent notches when the circuit is opened, and the pawl and detent occupying the same 85 notch when the circuit is closed.
10. In an instrument of the class described, the combination of a ratchet having a pawl and detent, means for actuating the pawl to operate the ratchet, and a circuit controlled by the relative movements of said pawl and detent, said pawl and detent occupying adjacent notches of the ratchet when the circuit is opened, and the pawl and detent occupying the same notch when the circuit is closed. 90
11. In an instrument of the class described, the said combination and structure as set forth in claim 10, in which said pawl and detent are included in said circuit. 100
12. In an instrument of the class described, the said combination and structure as set forth in claim 10, in which said detent presses the pawl into the notch.
13. In an instrument of the class de- 105 scribed, the combination of a ratchet having a pawl and detent which occupy adjacent notches on the ratchet when the pawl is retracted and which occupy the same notch after the ratchet is actuated, a spring to 110 actuate said pawl, and a magnet to retract said pawl.

Signed by me at Chicago, Illinois, this 24th day of March, 1917.

JOHN G. BLESSING.

It is hereby certified that in Letters Patent No. 1,250,782, granted December 18, 1917, upon the application of John G. Blessing, of Chicago, Illinois, for an improvement in "Electric Clocks," errors appear requiring correction as follows: In the drawings, Sheet 2, Figs. 5, 6, and 7, insert a *lead line* from the word "insulation" to the toothed ratchet-wheel *g*; in the printed specification, page 3, lines 46-47, claim 4, and lines 51-52, claim 5, strike out the word "substantially"; same page, lines 51-52, strike out the parentheses; and that the said Letters Patent should be read with these corrections therein that the same may conform to the record of the case in the Patent Office.

Signed and sealed this 12th day of February, A. D., 1918.

[SEAL.]

J. T. NEWTON,

Commissioner of Patents.
